UNITED STATES PATENT OFFICE.

JOHN D. ROSS, OF PORTLAND, MAINE, ASSIGNOR, BY DIRECT AND MESNE ASSIGNMENTS, TO ELECTRICAL STEAM RADIATOR CO., OF PORTLAND, MAINE, A CORPORATION OF MAINE.

ELECTRIC RADIATOR.

1,158,724.

Specification of Letters Patent.

Patented Nov. 2, 1915.

Application filed September 30, 1914. Serial No. 864,203.

To all whom it may concern:

Be it known that I, JOHN D. ROSS, a citizen of the United States, residing at Portland, in the county of Cumberland and State 5 of Maine, have invented certain new and useful Improvements in Electric Radiators, of which the following is a specification.

The object of the present invention is to provide an electric heating radiator which 10 may be used wherever necessary or desirable.

Applicant's device is designed to obtain the maximum of heat from the consumption of a minimum amount of electricity. This 15 he accomplishes by the special construction of the radiator, of the electric heating device and of their combination.

The drawing consisting of one figure, which has been chosen to illustrate the preferred form of the invention, is a side elevation partly in section.

In said drawing A is a series of radiator sections provided at the bottom with alined 20 openings B which form a water way between the radiator sections. The outer sections are provided with threaded collars C adapted to receive the threaded nuts D and E, respectively. The nut E carries a tube F, preferably in threaded engagement there- 25 with and extending through said water way and terminating close to the inner end of nut D or, as shown, in a circular recess G in the inner end of nut D. The tube F has preferably in the lower side near the inner 30 end thereof one or more ports H adapted to admit water from the water way to the chamber between said inner and outer tubes. The nut D carries a tube I within and con- 35 centric with tube F. In tube I is an elec- 40 tric heater J of any suitable construction. Leading out of tube F is a pipe K which re- 45 turns into the top of the radiator, as shown. This pipe may be made in sections and pro- 50 vided with a shut-off L. The radiator is provided with a steam operated regulator M of any desired construction.

The operation of the radiator is as fol- 55 lows: The radiator is supplied with a liquid to any desired height, which freely sur- 60 rounds the tube F and passes through ports

H into the narrow chamber between tube F and tube J, thus bringing only a comparatively thin film of the liquid in contact with the surface of the tube J which carries the heater, which limited quantity of the liquid 55 becomes quickly heated. When heated the liquid or steam passes out through pipe K into the top of the radiator. As the liquid gives out its heat by radiation from the outside of the radiator sections, it descends 60 again to the bottom of the radiator and through ports H into chamber J, thus providing a continuous circulation. The thin film of liquid in the chamber between the concentric tubes is very quickly heated with 65 the least possible consumption of electricity. The radiator sections become heated in the quickest possible time and are maintained economically at a high temperature. The radiator may be used for steam or hot water, 70 according to the amount of liquid used and the degree of heat required. When used for steam, the steam generated in the chamber between the concentric tubes passes through the circulation pipe into the radiator where 75 it condenses and returns to the bottom and again passes into the chamber between the concentric tubes, as before described.

I claim:

1. An electric radiator comprising a series of radiator sections with alined communicating openings at the bottom thereof, two concentric tubes in said alined openings, the outer tube being provided with an intake at one end and at the other end with a circulation pipe leading to the top of the radiator, and an electric heater located in said inner tube.

2. An electric radiator comprising a series of radiator sections having alined communicating openings in the bottom thereof, threaded nuts adapted to close said openings at the ends of the radiator, concentric tubes in said alined openings supported by said nuts, the outer tube being provided with an intake near the end and with a circulation pipe leading from the other end to the top of the radiator and the inner tube being closed to the radiator sections and provided with an electric heater.

3. In an electric heater, a liquid container, two concentric tubes located therein, the outside tube being provided with ports leading to the container and the inner tube closed to the container and an electric heater located in said inner tube.

In testimony whereof I affix my signature in presence of two witnesses.

JOHN D. ROSS.
